METHOD OF AND APPARATUS FOR SEPARATING COMPOSITE MATERIAL INTO ITS COMPONENTS

James H. Dickerson, New Philadelphia, Ohio

Application January 28, 1938, Serial No. 187,538

15 Claims. (Cl. 209—467)

This invention relates to pneumatic separators for granular or lump material adapted to separate materials having different specific gravities, such as for separating coal from slate and other refuse.

More particularly the invention relates to improvements in the separating means and the process of separation described and illustrated in my Patents Nos. 2,022,588 dated November 26, 1935; 2,033,690 dated March 1936; and in my co-pending application for patent Serial No. 38,105 filed on August 27, 1935, now Patent No. 2,128,918, dated September 6, 1938.

Separators of this kind have a previous reciprocating deck sloping to one side on which the bed of material being treated is partially supported above the deck by upward currents of air from below and the vibrations of the deck, caused by rocker arms and the reciprocating drive. The raw material is fed along the upper side of the deck, and the products are discharged along the lower side and the forward end of the deck. In the ordinary operation of a machine of this type the smaller lighter gravity material is mostly discharged near the rear end of the deck and the larger lighter gravity material tends to move forwardly, so the discharge of the lighter gravity material becomes gradually coarser towards the forward end of the table.

In the use of a primary separator sufficient air is used to carry the larger pieces of light gravity material over diagonal riffles, while the larger pieces of heavy gravity material drop to the deck and are directed by the riffles and the action of the deck at an angle to the flow of material passing over the riffles. This separates the coarser heavy gravity material from the mass, but much of the smaller heavy gravity material is blown over the riffles with the lighter gravity material. It has been the custom to screen the latter and re-treat the smaller size components, which still contain heavy and light gravity material, on another separator with reduced air currents, but this means extra screens, chutes, conveyors, bins, feeders, motors and more space, increasing both cost and maintenance.

One object of this invention is to transfer material from a primary deck direct to the upper side of a secondary deck, feeding the smaller material near the rear end of the primary separator to the deck of the secondary deck for re-treatment under different conditions, and discharging the larger cleaner material further forward to a previous plate, above the cleaning area of the sec-

ondary deck, thus obtaining more efficient cleaning over a greater size range on one machine.

A second important object is to check the discharge of the larger coal with the refuse.

5 A third important object is to remove more of the smaller refuse, by removing it separately from the sides of the riffles along which the coarser refuse moves forwardly.

A fourth important object is an improved riffle and stop to assist in the support of the bed of coal over the deck, and in the forward movement of refuse on the deck at an angle to the flow of clean coal.

With the above and other objects in view the 15 invention consists in a novel method of the kind described, and of apparatus including novel details of construction and combination of parts, both the method and apparatus being hereinafter described, and particularly pointed out in the claims, the apparatus being illustrated in the accompanying drawings wherein like characters of reference indicate like parts in the several views and:

In considering this invention, it will be described and claimed with particular reference to a coal cleaner for separating coal from refuse such as slate of greater specific gravity. It is, however, to be understood that neither the method nor the apparatus is restricted to this particular use but both method and apparatus are for separating a mixture having components of different specific gravities whereof coal is typical of a lighter material and slate of a heavier material. It is accordingly to be understood that wherever "coal" is used, in these specifications and the claims, it is to be interpreted in its broad sense as indicating the light components of a mixture, and "refuse" and "slate" are to be taken as referring to the heavier component of such a mixture.

In the embodiment of this invention as herein disclosed there is provided a surge bin 1 to hold a supply of raw material for the separator. A reciprocating feed plate 2 is one method of supplying a uniform feed to the cleaner. It may move with the cleaner or separately. A gate plate 3 is used with the feed plate to form the feed opening. The separator has a frame or sides 4, a deck 5 with openings 5a, and riffles 6. Other forms of riffles are shown as 6a, 6b, 6c, 6d, and 6e. The banking bar 7 is shown with its component parts, a spreader plate 8 and a concentrator plate 9. Gates 10 and 10a are used to make a line of separation in the streams of refuse and middlings. Coal is discharged from the deck sections A and B over tailing riffles 11 and discharge plates 12. A cut is made between middlings and clean coal by some form of adjustable divider 13. Slate is discharged over chute 14, while middlings go to the hopper 15 and clean coal to the hopper 16. A previous reciprocating plate 17 is attached above the deck 5 on section B to carry the coarser material delivered by section A. In the ordinary operation of a deck section such as A the smaller material of lighter gravity is discharged first and the material becomes gradually coarser towards the front end of the deck. An adjustable section 17a is provided to regulate the amount of material going to the plate 17, which has holes 17c for the escape of air coming up through the deck below. The plate may have an inclined section 17b. A combination deflector and banking bar 7a confines the large refuse from the upper deck, while finer refuse may bank against the other side. The coarse refuse is lowered part way to the lower deck by the plate 17b, and refuse along the upper side of section B may pass through the opening 7c and under the plate 17b, so the main stream of finer refuse will be covered by the coarser refuse, and not have to push against the latter. The air chest 18 is merely indicated. The air chest divisions 18a and 18b are fed from a common air supply with gates to each section. The air sup-

ply and gates are not shown as they are not a part of this invention and are well known. Air is thus adjusted to different sections. Support angles 19a working in guides 19 support rocker arms 21 which are adjusted vertically by small jacks 20 of conventional design. Eccentrics 22, eccentric rods 22a, and shaft 22b are driven by any common means from motor 23. Springs 24 are used to facilitate the forward movement of material and steady the deck. Middling chutes 25 may be arranged as desired. An elevator 26 may be used if it is desired to put middlings back on the deck or in the surge bin. A wedge shaped bar 27 is provided along the deck close to the concentrator plate 9 as a wearing strip and to start the material upward along the vertical curve in the concentrator plate.

For the feeder an air pipe 28 connects with the air chest 18, or any other source of air supply, such as hot air, and supplies air to the pipe 29. The air is controlled by a regulator 30. The member 28a may be flexible when it is attached to a stationary pipe. Air from the pipe 29 is discharged from the nozzle 31 across the stream of raw coal as it drops to the deck. This floats the lighter material forward where it will drop on top of the bed of material over the deck, while the heavier gravity material 34 will tend to drop more nearly the vertical, thus a partial separation is made before the material reaches the deck. Bolts 32 may be used to adjust the width of the opening in the nozzle 31. As the distance between the feed plate 2 and the deck 5 is not always constant a flexible coupling 33 is provided to keep air from blowing outwardly behind the feeder and to direct it across the feed stream. A housing 4, 33, and 35 may be provided instead of the pipes 28, 29 and the nozzle 31. The members 4, 33, and 35 form a seal so that most of the air rising through the openings 5a in this part of the deck is forced to pass laterally across the feed stream.

A laterally inclined deflector 36 is placed across a series of riffles where desired. It is supported by brackets 37 and may be adjusted vertically by the bolts 38 working in slots 39. The curved concentrator plate 9 is attached to members 40 having bolts 41 with thumb nuts 42 against bearing plates 42a. Riffles 6c have openings 43 along their tops. The riffles 6a are short members which cause the refuse to move in and out from the upper side of the deck. Rivets 44 set in the deck 5 have their front edge clipped to form a stop to keep material from slipping backward. Projections 45 are attached to the riffles 6e and are used with or without the rivet stops for the same purpose. The bar or pipe 46 with the straps 48 and the castings 49 form a seat hinge for the support of the deck frame, which permits the raising or lowering of the sides by screws or jacks 20 working in the guide and supporting framework. The casting is locked to the pipe 46 by the screws 47, and the casting 50 is the bearing for the toggles 21 carrying the machine. They may be set on the members 19 or on any suitable support.

The velocity of air on a section of deck along the lower side of a separator may be reduced by increased resistance 52, as indicated in Figure 16, or by any common means. At the end of said section a row of holes or slots 53a are made in the flat deck, or the deck is depressed to a valley 51 at an angle to the direction of the riffles. Below the openings 53a or at the bottom of this valley there may be a pipe or passageway 53 which

stratum. This will cause a thickening of the bed just back of the deflector. The inclined surface will help to support the material against it, and make it move more readily by gravity and the deck movement to the lower end of the separator. Refuse banked against the deflector may work down and pass under it, while coal may be pushed across the top of the deflector when it banks sufficiently. When the large coal drops over the top of the deflector, instead of following it to its lower end, the air currents still have a better chance to pick up the coal and help it over the riffles to the lower side of the deck, than if it had not been lifted by the deflector. Ahead of the deflector the bed of material on the deck will be lighter and the riffles lower so the air will have a further chance to raise the coal and permit it to pass by gravity to the lower side of the separator.

In an ordinary separator the air used to carry the larger pieces of coal over the riffles is also sufficient to carry much of the small refuse, and only the heavier gravity refuse of small size is discharged with the refuse. To correct this the quantity of air is reduced on a section of deck along the lower rear part of the deck. At the forward end of this section the deck is depressed in a valley below and lateral to the direction of the riffles, so that refuse leaves the sides of the riffles and enters this valley. At the bottom of the valley there is an opening controlled by a gate through which small refuse may go to the pipe or passageway 53, which conveys it laterally below the deck, and then forwardly below the deck to the point of main refuse discharge. This shortens the distance refuse has to travel along the riffles, and saves small refuse from being discharged further forward with the coal. Refuse too large to pass under the riffles, or into the pipe below the deck, will pass forward in the regular way to the end of the riffles. Another means would be to put holes of the size desired in the flat deck directly over the pipe or passageway.

The downwardly projecting tops of the riffles 6c help the air and the deck motion to support the bed of coal above the deck. It is especially desirable where the larger refuse has first been removed from the mass, and it is desired to re-treat the mass with a minimum of air to remove the smaller refuse. With stops placed above a flat perforated deck the sheets may be slightly thicker than can be used where the sheets are stamped with a waved surface. The holes are distorted by the stamping and the sheets break easily along the lines stamped. Waved sheets can be laid only in one direction. The deck wears out first along the banking bar, but a stamped sheet can not be laid parallel to it, so a new deck is usually installed. The flat sheets will reduce maintenance, and keep a better deck surface.

A means of adjusting the deck vertically is shown in Figures 12 and 13, but other means may be used. The rear pair of toggles being set more nearly the vertical than those forward give the forward part of the deck a greater vertical movement.

There has thus been provided a simple and efficient device of the kind described and for the purpose specified. It is obvious that changes may be made in the apparatus and method herein set forth without departing from the material principles of the invention. It is, therefore, to be understood that the invention includes any

apparatus and method which comes within the scope of the appended claims.

Having described my invention and set forth its merits what I claim and desire to secure by Letters Patent is:

1. In a separator for separating coal from refuse, a primary inclined reciprocable separating deck for removing heavier refuse from raw coal, a secondary inclined separating deck receiving the partially cleaned coal from the primary deck and separating additional refuse therefrom, riffles on said decks arranged at an angle to the direction of reciprocation, each of said decks being provided with a multiplicity of air jet apertures, means to supply air to said apertures, means to control the flow of air through the apertures to provide relatively high pressure air to the primary deck and relatively low pressure air to the secondary deck, means to reciprocate said decks, and a plate above the cleaning area of the secondary deck to carry the coarser part of the treated coal, being separated from the smaller material by the ordinary action of the primary deck, said plate to discharge its treated coal to the lower forward part of the said secondary deck.
2. In a pneumatic separator for separating coal from refuse, a primary inclined reciprocable deck for effecting a preliminary separation of the heavy gravity refuse from the raw coal, a secondary inclined reciprocating deck adapted to receive the feed stream from the primary deck and to separate additional refuse from the coal, said decks being pervious and having riffles at an angle to the direction of reciprocation, means to supply air through said pervious decks, means to adjust the supply of air to different sections of at least one of said decks, a passageway for refuse at the upper side of said secondary deck, and riffles on the forward part of said secondary deck projecting laterally and having their tops set approximately vertical to the surface of the deck and inclined upward in the direction of movement of the upper stratum of the bed of material on the deck, to assist the air in lifting the larger lighter gravity material over the riffles.
3. In a pneumatic separator for separating coal from refuse, a primary reciprocating separating deck having a banking bar and sloping to one side for effecting a partial separation of heavy gravity refuse from raw coal, a secondary reciprocating separating deck having a banking bar and sloping in the same direction as the primary deck, said secondary deck being adapted to receive the partially cleaned coal from the primary deck and to separate the remaining refuse from the coal, riffles on said decks arranged at an angle to the direction of reciprocation, each of said decks being provided with a multiplicity of air jet apertures, means to supply air to said apertures, a passageway for refuse at the upper side of said secondary deck, means for dividing the partially cleaned coal from the primary deck and delivering one part for re-treatment along the rear and upper part of the secondary deck, means to carry the remainder of the partially cleaned coal over and above the upper part of the secondary deck for re-treatment on the lower and forward part of the secondary deck.
4. In a separator for separating heavy gravity material from light gravity material, an upper reciprocable separating deck having a banking bar and sloping to one side for effecting a partial

takes the finer refuse coming from the upper side of the riffles, and conveys this refuse to the member 54 which carries the refuse forward below the deck level to the point of refuse discharge. A gate plate 55 provides an opening over which the larger refuse passes, and then moves forwardly along the deck. Bolts 56 in slots 57 will regulate the width of the opening. Openings 58 may be left in the riffles so that more fine refuse will work down to the passageway 53. Near the end of the banking bar 7 there is a gate 59 held in adjusted position by bolts 60 in slots 61, and gate 10a is attached to pivot bolt 62, and held in the clamped position by the nut 63. Pipe opening 64 provides an outlet for very fine material which passes through the openings 5a when the table is stopped, or air pressure is low, and then moves along the bottom of the air chest. A deflector 65 is used to direct material from the lower side of the deck to the opening 64.

The general operation of the primary deck A and the secondary deck B in Figure 1 is the same as described in my copending application, Serial No. 38,105, except for the substitution of the chutes 17 and 17a, and the riffles 6c for the coal supporting bars. The chute 17 is fixed above the cleaning surface on section B, while the chute 17a is bolted to the other members so it may be moved to adjust the amount of material which goes direct from section A to section B for re-treatment under reduced air currents and a different deck motion. The coarser material which goes to chutes 17 and 17a is carried by chute 17 above the deck surface below, where the finer material is being re-treated or the finer refuse is moving forwardly to the front end of the deck. The bed of smaller material on the deck will thin out under plate 17 and permit the discharge of the larger material on the cleaning area for re-treatment, or the larger material may be carried across the lower deck direct to the product hoppers. The chute 17 has perforations 17c to assist the air in its escape so that it does not blow sideways underneath and interfere with stratification. For the same reason it is well to keep the plate 17 as high as possible above the deck, and an inclined section 17b will help to give a better discharge to the deck below. The riffles 6b are made very low as there will be no large material on this part of the deck. The riffles 6c have an upper edge turned downward to assist the air and vibratory deck in carrying the bed of coal with its larger particles above the deck surface using a minimum of air. Slots 43 are provided for the escape of coal which may get under the projection and be raised by the lifting currents of air, while the small refuse continues to the ends of the riffles. Another form of riffles 6d is also used to reduce the air necessary to maintain a bed of coal over the deck, or above a section of deck, the bed containing a considerable size range from which the larger refuse has already been removed. The reduced air currents permit a more efficient separation of the smaller particles according to specific gravity. One or both of these forms of riffles may be used instead of carrying the larger sizes on the plate 17. They may be used also on a part of a single deck.

The refuse is trapped by riffles and guided forward by them with the deck action. As the path is somewhat inclined there is a slight tendency for slate to slip backwards. To move the refuse forward more quickly steps 45 may be attached to the bottom of the riffles along their upper side, which will give a more positive forward move-

ment to the refuse. Rivets 44 with their forward edge clipped may be inserted in the deck bottom for the same purpose. In moving forward slate may pass over the rivet heads, but after it is over the clipped edge offers a stop so that the slate can not move back readily. Either one of these means or both of them together may be used to obtain a quicker movement of the refuse.

The preliminary treatment of coal as it passes from the feeder to the deck is covered by my Patent No. 2,022,588, but an improved arrangement is shown in Figure 4. A similar arrangement is shown in Figures 5 and 6, except that air behind the feed stream which has passed upwardly through the holes 5a in the deck is practically surrounded by the parts 4, 5, 33, 35 and the feed stream; so that it must pass forwardly through the feed stream which flows between the members 35.

Between the concentrator plate 9 and the wedge shaped bar 27 there is a space through which the air rises from the air chest to pass along the upper side of the plate 9 against which the refuse 34 is banked. The forward motion of the deck, causing the refuse to bank against the banking bar concentrator plate 9, together with the wedge shaped bar 27 and the inwardly curved and upwardly inclined concentrator plate, with direct currents of air along its lower side, cause the refuse stream to move upwardly and then along the curve rearwardly towards the deck, and to rise to its greatest height along the under side of the concentrator plate. With sufficient refuse the upper part of the refuse stream along the concentrator plate will continue to drop off and move backward and downward towards the deck. This will give the stream of refuse a slowly rotating motion as it moves forwardly along the banking bar. The concentrator plate may be set lower at its discharge end and give the refuse stream a constantly changing cross section. These various means will bring different parts of the refuse stream to the surface as it moves ahead and give any coal trapped with the refuse a chance to escape and move downwardly back to the deck, and also tend to regulate and make the refuse stream move more uniformly. The latter is quite important as a change in the refuse stream calls for an adjustment of the gates to divide refuse, middlings, and clean coal. When refuse is directed back from the banking bar towards the deck it will sink to the bottom and be again brought back to the banking bar. This helps to keep a good refuse line along the banking bar, which will tend to crowd out and hold the lighter material back and give a more uniform discharge of refuse.

In a separator of this type the larger coal works forwardly. To get it over the riffles the air may be increased and the height of riffles reduced as shown in Figure 4. This is common practice but some of the larger coal still passes to the end of the riffles with the refuse. To further correct this difficulty the rear pair of toggles is set more nearly vertical than the forward pair, which gives a greater vertical motion for the forward part of the deck. This is to help the air to lift the coal over the riffles. In addition to this a lateral and forwardly inclined deflector 36 is placed across a series of riffles to help make a more complete separation. It may be adjusted vertically so only a certain size or a given quantity may pass underneath. The lower end is set back so it will slightly bank and deflect the upper

separation of the heavy gravity material from the light gravity material, a lower reciprocable separating deck having a banking bar and sloping in the same direction as the upper deck, said lower deck being adapted to receive the partially cleaned material from the upper deck, and to separate additional heavy gravity material from the light gravity material, riffles on said decks arranged at an angle to the direction of reciprocation, each of said decks being supplied with a multiplicity of air jet apertures, means to supply air to said apertures, means to reciprocate the decks, a passageway for the heavy gravity material at the upper side of the lower deck, a discharge chute extending from the lower side of the upper deck and over said passageway on the lower deck, a plate over and above the cleaning area of the lower deck to carry the coarser partially cleaned material from the primary deck to a point on the secondary deck where it can be re-treated without interfering with the re-treatment of the smaller partially cleaned material from the primary deck, the heavy gravity material passing along the upper sides of both decks and the banking bars to discharge at the extreme end of the lower separator, while the lighter gravity material is discharged along the lower side of the lower separator.

5. In a separator for removing refuse from coal, a primary inclined reciprocable deck for effecting a preliminary separation of heavier refuse from coal, a secondary inclined separating deck receiving a stream of partially cleaned coal from the primary deck and separating additional refuse therefrom, said secondary deck being provided with a passageway for refuse adjacent its upper side, means for making a division between the coarser and finer treated coal from the primary section and to carry the coarser material over and above a section of the lower separating deck used for the re-treatment of the finer treated coal from the primary deck, riffles on said decks arranged at an angle to the direction of reciprocation, each of said decks being pervious, means to supply and control the flow of air through said decks to provide a relatively large quantity of air to the primary deck and a relatively small quantity of air to the secondary decks, means to reciprocate said decks, and means for remixing the coarser treated coal and the remaining finer treated coal on the lower forward part of the secondary deck for further re-treatment.

6. A dry separating apparatus having a laterally inclined pervious reciprocating deck provided with diagonal riffles, said deck having a section depressed to form a valley below and across a series of riffles, to permit small refuse to leave and travel underneath said riffles, said valley providing for the movement of small refuse forward and downward along the deck bottom at an angle to the direction of the riffles, said riffles directing the coarser refuse forward and upward.

7. A dry separating apparatus having a laterally inclined pervious reciprocating deck provided with riffles and means to supply air through the deck, said deck having a valley crossing underneath a series of riffles, the section of said deck approaching said valley being provided with relatively weak currents of air passing upwardly from below, and the section of deck ahead of said valley having stronger upward currents of air, along the bottom of said valley a gate to regulate the size and quantity of material leaving the sides of the riffles to be conveyed laterally below the riffles towards the lower side of the

deck, and then forwardly to the point where the main refuse stream is discharged.

8. A dry separating apparatus having a pervious inclined reciprocating deck provided with riffles, and upward currents of air from below, said deck having a deflector comprising a narrow plate inclined downward towards the lower side of the deck, and laterally upward towards the forward part of the deck, and set above and across a series of riffles, said plate being spaced to allow refuse and a limited amount of coal to pass underneath, and slightly bank the stratum of coal above, the double slope of said plate assisting the air and the motion of the deck to lift and convey the coal over the riffles more rapidly to the lower side of the deck, and save large coal from being discharged with the refuse.

9. The method of separating raw materials of different specific gravities and size, such as raw coal, comprising feeding the material in a thin freely flowing stream upon an inclined reciprocating support, conveying, spreading, and stratifying the material upon the support by a reciprocating rocking motion, and currents of air directed through the support, causing the refuse to move along guides diagonally upward and forward, and the lighter gravity material to move forward and downward becoming gradually coarser towards the forward part of the bed, reducing the air pressure under a portion of the support carrying the finer material for re-treatment, moving the resulting refuse along guides carrying coarser refuse, and then removing the finer refuse from the guides and causing it to move at an angle from the coarser refuse, and causing the finer refuse to move forward and downward along the reciprocating support to a point of discharge, to avoid remixing the finer refuse with the coal where the coal is coarser and the air pressure is greater.

10. In a separator for separating refuse from coal, a pervious inclined reciprocable deck with riffles, and means to force air upward through said deck, said riffles rising from the deck but having tops inclined downward towards the deck and the flow of coal, said tops being inclined to assist the air in lifting the larger lighter gravity material over the riffles, and slots in the tops of said riffles for the escape of small coal.

11. A dry separating apparatus having a laterally inclined pervious reciprocating deck provided with riffles, said deck having a series of riffles with a line of openings for the lateral escape of small refuse from the upper sides of said series of riffles, and below and ahead of said openings a passageway disposed transversely to the riffles and depressed to form a valley in the deck, said passageway to collect the small refuse and convey it laterally below and across a second series of riffles, together with small refuse from said second series of riffles, to the lower side of said deck.

12. A dry separating apparatus having a laterally inclined pervious reciprocating deck provided with diagonal riffles, said deck having a section depressed to form a valley at an angle to the riffles, said valley providing an opening between the deck and the riffles for the escape of small refuse to move along the bottom of the deck towards the lower side of the deck, while the coarser refuse follows the riffles towards the upper side of the deck.

13. A dry separating apparatus having a laterally inclined pervious reciprocating deck provided with diagonal riffles, said deck having a section

depressed to form a valley below and across a series of riffles, to permit small refuse to separate from the coarser refuse and travel underneath said riffles, said valley providing for the movement of small refuse along the bottom of the deck at an angle to the direction of the riffles, and in the direction of the coal flow over the riffles, while the coarser refuse continues to move forward along the riffles.

14. A dry separating apparatus having a laterally inclined pervious reciprocating deck provided with diagonal riffles and means to supply air through the deck, said deck having a line of openings spaced to be just above the riffles, the section of the deck approaching said line of openings being provided with relatively weak currents of air passing upward from below, and the section of the deck ahead of said line of openings to have stronger upward currents of air, and underneath said line of openings a passageway disposed transversely to the riffles, said passageway to remove the smaller size refuse from the riffles and convey it laterally below the riffles to the lower side of the deck, and then forward to unite with the main refuse stream.

15. The method of separating raw materials of different specific gravities and size, such as raw coal, comprising feeding the material in a thin freely flowing stream upon an inclined reciprocating support, conveying, spreading, and stratifying the material upon the support by a reciprocating rocking motion, and currents of air directed through the support, causing the refuse to move along guides diagonally upward and forward, and the lighter gravity material to move forward and downward becoming gradually coarser towards the forward part of the bed, reducing the air pressure under a portion of the support carrying the finer material for re-treatment, moving the resulting refuse upward and forward along a series of guides carrying coarser refuse, and then removing the finer refuse from the guides and causing it to move downward and forward along the reciprocating support, so as to avoid remixing the finer refuse with the coal where the coal is coarser and the air pressure is greater.

JAMES H. DICKERSON.
